UNITED STATES PATENT OFFICE

IRVEN H. WILSEY, OF CHICAGO, ILLINOIS, ASSIGNOR TO JAMES B. TUTHILL, OF CHICAGO, ILLINOIS

PUMP

Application filed January 11, 1926. Serial No. 80,435.

The invention relates to improvements in rotary pumps for transmitting oil and other liquids.

A general object of the invention is to provide a new and improved pump which is adjustable to vary and reverse the flow of liquid, and which serves to meter the flow of liquid.

Another object is to provide a pump of the above character having no valves, such as check valves, thereby requiring power only to pump the oil, and furthermore preventing the flashing of volatile liquids on the suction stroke due to the added partial vacuum necessary to overcome ordinary valve resistance.

In many prior rotary pumps having reciprocating plungers, the outer ends of the cylinders open directly into the inlet and exhaust chambers so that when the pump is operated at a high speed centrifugal force will cause partial evacuation of the cylinders on the suction stroke, thereby lowering the effective capacity of the pump and limiting the speed at which it can be successfully operated. An important object of the present invention is to provide a pump which can operate at a high speed without such evacuation, and in which centrifugal force will cause pressure on the piston heads during the suction stroke thereby causing the pump to operate at maximum capacity.

Other important objects reside in the provision of a rotary pump which even though of a large size and operating at a high speed has a low rubbing velocity at the valve ports, which has a relatively small area of friction surfaces at any place, and in which all principal thrusts are taken up by ball or roller bearings revolving at proper speeds irrespective of the speed of the pump.

Another object is to provide a pump which when conveying volatile liquids will not leak liquid or vapor into the surrounding air, and in which liquid seals are provided to prevent air from being drawn into the cylinders on the suction stroke.

Still other objects of the invention are to taper the ports and the ends of the pistons so as to eliminate air and vacuum pockets and consequently to prevent hammer; in which all

centrifugal forces in the pistons are balanced; in which side pressure between the pistons and cylinders is reduced, thereby minimizing wear, retaining a lubricating film and preventing noise; and in which leakage past the pistons is utilized to lubricate other parts of the pump and to lubricate such parts in direct proportion to the work being done.

A further object is to provide a novel pump which is simple and inexpensive in construction, which is efficient in operation over a wide range particularly at partial loads since no part of the liquid is by-passed, and which can be used as an engine.

Further objects and advantages will become apparent as the description proceeds.

Figure 1 is a vertical sectional view of a pump embodying the features of my invention.

Fig. 2 is a front end view thereof.

Fig. 3 is a sectional view taken along line 3-3 of Figure 1.

Fig. 4 is a sectional view of the valve construction taken along line 4-4 of Figure 1.

Fig. 5 is a sectional view of the valve construction taken along line 5-5 of Figure 1.

Fig. 6 is a detail sectional view taken along line 6-6 of Figure 1.

While the invention is susceptible of various modifications and alternative constructions, I have shown in detail the preferred embodiment, but it is to be understood that I do not thereby intend to limit the invention to the specific form disclosed but aim to cover all modifications and alternative constructions falling within the spirit and scope of the invention as expressed in the appended claims. Referring more particularly to the drawings, the pump comprises a suitable casing 10, a rotor 11 mounted in the casing and having a plurality of cylinder and piston units, and means preferably a pin 12 adjustably mounted in the casing and serving to control the actions of the pistons.

The casing 10 preferably is cylindrical in form, and is closed at one end by a ribbed wall 13. A cover 14 is removably secured to the other end of the casing by bolts 15, and is formed with strengthening ribs 16. Formed

at spaced points on the peripheral wall of the casing are a plurality of stands 17 for supporting the pump on a suitable support (not shown).

5 Centrally formed on the outside of the wall 13 and opening therethrough is an elongated bearing and valve casing 18 having a conical valve seat 19. The outer end of the casing 18 is closed by an end cap 20 provided with a 10 suitable stuffing box 21. Formed on one end of the rotor 11 is an elongated tapered hub 22 which fits closely against the valve seat 19, and the outer end of which is reduced in size as indicated at 23. The hub 22 is rotatably 15 mounted at its ends in suitable ball bearings 24 and 25, of which the bearing 24 is positioned in an annular space 26 formed in the inner end of the casing 18. The bearing 25 is a partial thrust bearing, and is positioned 20 on the reduced end 23 of the hub and in an annular notch 27 cut in the outer end of the casing 18. Extending through the hub 22 to which it is rigidly secured by a key 28 is a drive shaft 29 which extends outwardly 25 through the stuffing box 21 for connection with a suitable source of power (not shown). The hub 22 is held against the seat 19 by a pair of lock nuts 30 turned onto a threaded section 31 of the shaft 29 in a chamber 32 30 formed in the end cap 20, and engaging the outer end of the bearing 25. Wear on the hub 22 or seat 19 can be taken up by adjusting the nuts 30, a space being left between the end of the hub and the bearing 25 to permit 35 this adjustment. By supporting the rotor 11 through the hub 22, the former can be driven at an extremely high speed without subjecting the bearings to an excessive speed, and the friction areas are relatively 40 small, thereby permitting efficient operation with minimum wear and loss of power through friction.

A plurality of cylinders, four cylinders 33^a, 33^b, 33^c, and 33^d in the present instance, 45 are formed at the periphery of the rotor 11. These cylinders are radial, are spaced 90° apart, and the diametrically opposed cylinders are in alignment. For ease in assembling, the cylinders are split, outer semi-cylindrical caps 34^a, 34^b, 34^c, and 34^d being secured by bolts 35 to semi-cylindrical brackets 36^a, 36^b, 36^c, and 36^d on the rotor 11. The outer ends of the cylinders are closed by end caps 37^a, 37^b, 37^c, and 37^d secured thereto 50 by bolts 38. The inner ends of the cylinders are open to the atmosphere.

The outer ends of the cylinders are respectively connected by pressure fluid passages 39^a, 39^b, 39^c, and 39^d, extending inwardly 55 through the brackets 36^a, 36^b, 36^c, and 36^d and longitudinally through the hub 22, with valve ports 40^a, 40^b, 40^c, and 40^d in the peripheral surface of the hub next to the valve seat 19. Each valve port is located in the 60 same plane and on the same side of the rotor

11 as the cylinder with which it is connected. Surrounding the hub 22 at the valve ports is a valve chamber 41 formed in the casing 18, and divided into two parts by two diametrically opposed lands 42 and 43. Opposite sides of the chamber 41 open respectively into passages 44 and 45 which are adapted to be connected to suitable fittings (not shown) adapted to be attached to the casing 18 by flanges 46. Fluid may be admitted through one of the passages 44 and 45, and discharged through the other, the specific direction of flow depending upon the action of the pump. It will be evident that the hub 22 constitutes a valve which upon rotation of the rotor will successively and alternately connect the opposed cylinders to opposite sides of the chamber 41. By being located near the axis of rotation, the valve surfaces have a low rubbing velocity, thereby permitting a high pump speed without limiting the latter.

To minimize leakage of fluid or air past the bearing surfaces between the ball bearing 25 and the valve ports, an annular plate 47 is positioned against the inside of the ball bearing, and an annular ring 48 is mounted in a notch 49 in the outer end surface of the hub 22 next to the plate. A plurality of coil springs 50 positioned in bores 51 opening into the notch 49 press the ring 48 against the plate 47. Fluid will be trapped by the ring 48 in the space 52 between the outer end of the hub 22 and the plate 47, and will seal the space between the hub and the seat 19. The small amount of fluid that may pass through to the chamber 32 may be drained away through an opening 53 adapted to be connected to a fluid return pipe (not shown). To prevent leakage between the ball bearing 24 and the chamber 41, an annular notch 54 is cut in the inner end of the housing 18 next to the inner raceway of the ball bearing, and an annular ring 55 is positioned in a groove 56 cut in the side of the notch. The ring 55 is pressed into engagement with the inner raceway of the ball bearing 24 by a plurality of springs 57 located in bores 58 opening into the groove 56. Fluid trapped by the ring 55 in the groove 54 next to the hub 22 will seal the space between the ball bearing 24 and the chamber 41. Any fluid that may collect in the housing 10 may be drained away through an opening 59 adapted to be connected to a suitable return pipe (not shown). By minimizing leakage, the efficiency of the pump is materially increased.

Mounted in the cylinders 33^a, 33^b, 33^c, and 33^d, are pistons 60^a, 60^b, 60^c and 60^d respectively. Each piston has a core 61 in its end, the outer end of which is slightly pointed to avoid hammer. The opposed cylinders 60^a and 60^c, and 60^b and 60^d are rigidly connected by rectangular yokes 62 and 63 respectively. These yokes are offset in opposite di-

rections from the centers of the pistons, and are movable at right angles to each other in a space 64 in the center of the rotor 11.

The relative movement of the pistons in the cylinders is controlled by the pin 65 which is secured in ball bearings 66 and 67 mounted in turn in blocks 68 and 69 slidably disposed in the yokes 62 and 63 respectively. By providing the yoke and block construction, an axial thrust over a substantial area is applied to the pistons, thereby eliminating lateral forces and obtaining a reduced pressure between the sides of the pistons and cylinders. As a result, power losses due to friction are reduced, and a lubricant having a low resistance to pressure may be used.

To minimize leakage from the cylinders past the pistons, peripheral grooves 70 are cut in the pistons, one groove for each piston, and these grooves are connected by passages 71 extending longitudinally through the pistons to the bearing surfaces between the yokes 62 and 63, and the blocks 66 and 67. Fluid passing to the grooves 70 is trapped there, and part thereof is used to lubricate the bearing surfaces just referred to. The amount of lubrication will be directly proportional to the work performed by the pump. To further minimize leakage the inner edges of the pistons are chamfered at 72, and the inner peripheral edges of the cylinders are formed with notches 73. Due to centrifugal force any fluid leaking past the pistons will be held in the chamfered spaces 72 and in the notches 73. Any fluid falling into the casing 10 can be drained away through the outlet 59. By minimizing leakage, power losses are reduced, the pump capacity is increased, and the efficiency is in general increased. Elimination of leakage is particularly important where volatile oils are being pumped, as in oil refineries, for such volatile oils, if leaking to the atmosphere, may ignite.

If the pin 65 is concentric with the shaft 29, no movement of the pistons will result upon rotation of the rotor 11. If the pin 65 is eccentric to the shaft 29 then movement will result with a consequent pumping action. Any suitable means for adjustably supporting the pin 65 may be provided. In the present instance, the pin is mounted in an adjustable block 74 disposed in opening 75 in the center of the cover 14. The opening is surrounded by a flange 76. The block has upper and lower guide pins 77 and 78, two of each, which extend slidably through bearings 79 formed in the upper and lower sides of the flange 76. Mounted on the outer end of the pin 65 is a block 80 which is adjustably disposed in a yoke 81 formed on the short arm of a bell crank lever 82. The latter is mounted on a pivot 83 on the cover 14, and the long arm has a handle 84 for adjusting the pin 65. The handle 84 is adapted to be clamped in adjusted position, when a con-

stant flow is desired, by means of a wing nut 85 thereon engaging a bolt 86 which is slidable in a slotted arcuate member 87 on the cover. The pin thus is adjustable in a straight line across the axis of the shaft 29. To cause each piston for any two opposed ports to be at the end of its stroke when the ports are cut off by the lands 42 and 43, this line of movement must be in the plane of the lands.

The pin 65 is easily adjustable since when any two ports are cut off by the lands, free end movement of the corresponding pistons is permitted. The only force on the pistons at that time is lateral, and the resistance presented by the fluid trapped in the end of one piston is counterbalanced by the thrust of the other pair of pistons. When all the ports are open, the thrusts of the pistons are opposed, thereby still avoiding resistance to the adjustment of the pin 65.

In operation, when the pin 65 is in line with the shaft 29 no pumping action results, the pistons remaining stationary in the cylinders and rotating on the ball bearings 66 and 67. Assuming that the shaft 29 is rotating in a clockwise direction, as the pin 65 is adjusted into a position above the shaft 29, as shown in Figure 1, fluid will be drawn in through the passage 45 and discharged through the passage 44. Upon rotation of the rotor, one of each pair of pistons moves inwardly as its port moves across the passage 45, thereby creating a suction, and the other piston moves outwardly as its port crosses the passage 44, thereby expelling the fluid in its cylinder. When the two pistons of a pair are in a vertical position as shown in Figure 1, all the fluid in the upper cylinder has been expelled and the lower cylinder has been filled. Due to the radial direction of the passages 39 (a to d) in the brackets 36 (a to d), a centrifugal force resulting from the rotation of the rotor tends to fill the ends of the cylinders. This results in increasing the efficiency of the pump since no waste of space in the cylinders obtains. As the pin 65 is adjusted into a position below the shaft 29, the directional flow of the fluid will be reversed, i. e. fluid will be admitted through passage 44 and discharged through passage 45. The rotation of the shaft however will continue in the same direction. The extent of reciprocation of the pistons and hence the volume of the flow of liquid is determined by the degree of eccentricities of the pin 65 to the shaft 29. It will be seen that by this construction a very fine control of the flow in volume and direction is available.

It will be seen that I have provided a simple and inexpensive pump which can be easily assembled, easily repaired, and which is extremely efficient in operation. A minimum loss of power due to friction and leakage results, and therefore the maximum ca-

pacity is available. The pump due to the prevention of excessive leakage is particularly adapted for use where volatile oil is to be transmitted. All the rotative parts are mounted in ball bearings. The ball bearings are subjected to relatively low speeds of rotation. This is also true of the valve surfaces. Because of the low resistance due to the small bearing surfaces which are required the pump can be easily started, particularly if the pin is moved into central position so that no power need be expended in actual pumping. Perfect control of the flow without the use of by-pass valves is provided, thereby utilizing all of the power in the actual transmission of fluid.

I claim as my invention:

1. A pump having, in combination, a casing having a bearing member in one end thereof, said bearing member being formed with a valve chamber, lands dividing said chamber into two parts, a rotor having a hub rotatably mounted in said bearing, said rotor having a plurality of cylinders at its periphery, a plurality of passages extending substantially radially and inwardly from the outer ends of said cylinders through the end wall of said rotor and lengthwise of said hub, and terminating in ports in the peripheral surface of the hub, said ports being adapted to be moved successively into communication with opposite sides of said valve chamber, a plurality of pistons one mounted in each cylinder, and means operative to reciprocate said pistons in said cylinders upon rotation of said rotor.

2. A pump having, in combination, a casing having a bearing member in one end thereof, said bearing member being formed with a valve chamber, lands dividing said chamber into two parts, a rotor having a hub rotatably mounted in said bearing, said rotor having a plurality of cylinders at its periphery, a plurality of passages extending substantially radially and inwardly from the outer ends of said cylinders through the end wall of said rotor and then lengthwise of said hub, and terminating in ports in the peripheral surface of the hub, said ports being adapted to be moved successively into communication with opposite sides of said valve chamber, a plurality of pistons, one mounted in each cylinder, and means operative to reciprocate said pistons in said cylinders upon rotation of said rotor, said means being adjustable across the axis of rotation to reverse the flow of fluid and to vary the amount of flow in either direction.

3. A pump having, in combination, a valve casing, bearings in opposite ends of said valve casing, said valve casing having a valve chamber therein, lands dividing said chamber into two opposed parts, a rotor having a hub rotatably mounted in said bear-

ings and fitting against the inner surface of said casing, said hub having a plurality of ports movable across said lands into and out of communication with opposite sides of said chamber, cylinders on said rotor, said rotor having a plurality of passages, one connecting each cylinder with one of said ports, a plurality of pistons, one in each cylinder, and means engaging said pistons and adapted to cause said pistons to reciprocate upon rotation of said rotor, said means being adjustable in an axial plane through said lands into and out of eccentricity with the axis of rotation.

4. A pump having, in combination, a casing, a rotor journaled in said casing and having a plurality of radial cylinders, said cylinders being arranged in pairs of diametrically opposed cylinders, pistons slidably mounted in said cylinders, opposed pistons being connected by a lateral yoke, a plurality of sliding blocks, one mounted in each yoke, a pin rotatably engaging said blocks for movement therewith, said pin being mounted in said casing for adjustment into eccentric relation with the axis of rotation, and valve means for admitting and discharging fluid to and from said cylinders in timed relation to the reciprocation of said pistons.

5. A pump having, in combination, a casing, a rotor mounted in said casing and having a plurality of cylinders at its periphery, a plurality of pistons, one in each cylinder, the outer ends of said pistons being tapered to reduce hammer, means eccentric to the axis of rotation engaging said pistons to cause reciprocation of the latter upon rotation of said rotor, and means for admitting fluid to and from said cylinders.

6. A pump having, in combination, a bearing, a rotor mounted in said bearing and having a plurality of cylinders at its periphery, a plurality of pistons, one in each cylinder, means engaging the inner ends of said pistons, said means being capable of being positioned in eccentric relation to the axis of rotation to cause reciprocation of said pistons in said cylinders, and a plurality of passages, one in each piston extending from the inner surface of the associated cylinder inwardly to the bearing surfaces between said piston and said means, said passage serving to direct fluid leaking partially past said piston to said bearing surfaces to lubricate the latter in direct proportion to the work done by said pump, and means for admitting and discharging fluid to and from said cylinders.

7. A pump having, in combination, a casing, a rotor mounted in said casing, said rotor having a plurality of radial cylinders closed at their outer ends, a plurality of pistons, one in each cylinder, means between the inner ends of said cylinders, said means engaging said pistons and being adapted to be moved

- into eccentric relation to the axis of rotation to cause reciprocation of said pistons, notches formed in the inner ends of said cylinders and the heads of said pistons, said notches being adapted to be filled with fluid leaking past said pistons to minimize said leakage, and valve means for directing pressure fluid to and from the outer ends of said cylinders. 6
8. A pump having, in combination, a valve casing having a valve chamber and a valve seat, lands dividing said chamber into two parts, a rotor having a hub engaging said seat, said hub having ports adapted to be moved across said lands and successively 10 into communication with opposite sides of said chamber, piston and cylinder units on said rotor, means for actuating said pistons in said cylinders upon rotation of said rotor, said rotor having passages, one connecting 15 each cylinder with one of said ports, and means confining a small space at each end of said seat to seal the spaces between said seat and said hub at opposite sides of said chamber. 20
- 25 9. A pump having, in combination, a valve casing having a valve chamber and a valve seat, lands dividing said chamber into two parts, a rotor having a hub engaging said seat, said hub having ports adapted to be moved across said lands and successively 30 into communication with opposite sides of said chamber, piston and cylinder units on said rotor, means for actuating said pistons in said cylinders upon rotation of said rotor, 35 said rotor having passages, one connecting each cylinder with one of said ports, and means for sealing the space between said seat and said hub at one side of said chamber to reduce the leakage of fluid therethrough. 40
- 45 10. A pump having, in combination, a bearing, a rotor journaled in said bearing and having a plurality of cylinders extending toward the periphery thereof, a plurality of pistons, one mounted in each cylinder, a block slidably adjustable in one end of said casing, a pin in said block, said pin engaging said 50 pistons and when located eccentrically of the axis of rotation serving to cause reciprocation of said pistons in said cylinders, valve means for directing pressure fluid to and from said cylinders, and means for adjusting said block in a plane passing through the axis of rotation. 55
- 60 11. A pump having, in combination, a combined bearing and valve member having a conical seat and a valve chamber opening through opposite sides of said seat, a rotor having a conical hub engaging said seat and having a plurality of ports opening through its peripheral surface for movement into successive communication with opposite sides of 65 said valve chamber, means for adjusting said hub axially in said member to take up wear or looseness, a plurality of piston and cylinder units in said rotor, and passages connect- 70 75 80 85 90 95 100 105 110 115 120 125 130
- ing said ports to said piston and cylinder units, said piston and cylinder units being operable to draw fluid from one side of said chamber and to discharge it to the other side of said chamber upon rotation of said rotor. 70
- In testimony whereof, I have hereunto affixed my signature.
- IRVEN H. WILSEY.
